(57) **CLAIM**

The ornamental design for a coffee capsule, as shown and described.

DESCRIPTION

FIG. 1 is a first side view of a first embodiment of a coffee capsule;

FIG. 2 is a second side view thereof, rotated by a first angle from the first side view;

FIG. 3 is a third side view thereof, rotated by a second angle from the first side;

FIG. 4 is a fourth side view thereof, rotated by a third angle from the first side view;

FIG. 5 is a top view thereof;

FIG. 6 is a bottom view thereof;

FIG. 7 is a top side perspective view thereof; and,

FIG. 8 is a bottom side perspective view thereof.

Any broken lines in the figures illustrate portions of the coffee capsule that form no part of the claimed design.

1 Claim, 8 Drawing Sheets
